UNITED STATES PATENT OFFICE.

JOSEPH V. HORN, OF DOUGLASSVILLE, PENNSYLVANIA.

COIN INDICATING AND CHECKING MECHANISM.

1,407,541.

Specification of Letters Patent. Patented Feb. 21, 1922.

Application filed December 4, 1920. Serial No. 428,412.

To all whom it may concern:

Be it known that I, JOSEPH V. HORN, a citizen of the United States, residing at Douglassville, county of Berks, State of Pennsylvania, have invented a new and useful Coin Indicating and Checking Mechanism, of which the following is a specification.

In cafeterias in which different articles are sold under the self serve system, it has been deemed essential to employ a checker to determine the proper payment and tender the check to the purchaser, the payment of the amount due being made to the cashier before leaving the restaurant; or, in some systems of self serve restaurants it is necessary to present the purchaser with a blank check upon entering and the amount is registered upon this check by the attendant who serves the articles desired. The purchaser makes payment to the cashier before leaving the restaurant. In devices now in operation it is necessary to employ a checker and a cashier.

It is the purpose of my present invention to devise a check upon mistakes by the attendant or purchaser by means of an intermediate-coin rest between the points where the coins are first visible and the money drawer where such coins are finally deposited, thus giving the manager of the restaurant ample opportunity to check up the amount to be deposited, as the money remains visible until the following purchase is made.

With the above and other objects in view as will hereinafter more fully appear, my invention comprehends a novel construction and arrangement of coin indicating and checking mechanism.

It further comprehends a novel construction and arrangement of a coin chute having a transparent portion, a novel construction and arrangement of a support for retaining the coins passing through the chute above said support so that they will be readily visible to the attendant, customer and the manager of the restaurant, novel means for actuating such support, and a novel construction of a casing whereby after the support has been moved the coins will still be visible to the customer and to the manager of the restaurant.

Other novel features of construction and advantage will hereinafter more fully appear

in the detailed description and the appended claims.

For the purpose of illustrating my invention, I have shown in the accompanying drawings a typical embodiment thereof which is at present preferred by me, since this embodiment will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in perspective, a coin indicating mechanism, embodying my invention.

Figure 2 represents a front elevation of a portion of my device with a cover plate removed.

Figure 3 represents, in side elevation, a cam member employed.

Figure 4 represents a section on line 4—4 of Figure 1.

Figure 5 represents a section on line 5—5 of Figure 2.

Figure 6 represents a section taken substantially on line 5—5 of Figure 2 with certain parts omitted, and showing more clearly the manner in which the rotation of the coin support is effected.

Figure 7 represents a section on line 7—7 of Figure 2.

Figure 8 represents, in section, another embodiment of my invention.

Similar numerals of reference indicate corresponding parts.

Referring to the drawings.

1 designates a coin chute which is formed in sections and consists of a front member 2 and a rear member 3 which are connected together by means of fastening devices 4. The juxtaposed walls of the members 2 and 3 contribute to form a coin chute 5 and are preferably recessed or slotted for this purpose. The coin chute is provided with a sight opening 6, it being seen that the front member 2 is provided with a recess 7, while the rear member 3 is provided with a recess 8, and that the members at one side are slotted, as indicated at 9, in order that the glass or other transparent members 10 and 11 respectively can be inserted in place through the slot 9. The transparent mem-

bers 10 and 11 which contribute to form the sight opening are spaced from each other by means of spacing strips 12. The transparent members 10 and 11 are retained in position by means of a block 13 which closes the outer end of the slot 9, and this block is secured in position by means of a fastening device 14.

The members 2 and 3 which form the coin chute are slotted, as indicated at 15, see more particularly Figure 4, in order to form a space to receive a rotatable coin support 16 which is mounted on a shaft 17, the ends of which are journaled in slots 18 formed in the chute members 2 and 3, see more particularly Figures 1 and 2.

The coin support 16 is formed of two end discs 19 which are slotted to receive the ends of the plates 20 and 21, respectively, which form blades disposed at substantially right angles to each other so that four pockets 22 are formed. 23 designates the rear bracket to which is connected a cover plate 24 by means of fastening devices 25. The rear bracket plate has side bars connected to the rear chute member 3 and one of these bars is slotted, as indicated at 26, see Figure 5. 27 designates a front bracket which has a top bar 28 and depending side bars 29 one of which is grooved, as indicated at 30. The front bracket 27 is provided with the side wings 31 which are braced by a cross bar 32, and this cross bar and the top cross bar 28 form a support for a transparent plate 33 which is secured in position by means of a cover plate 34 which latter is secured to the front bracket 27 by means of screws 35 and to the front chute member 2 by means of screws 36, it being seen that this cover plate 34 is apertured as at 37. The rear bracket 23 with its cover plate 24 and the front bracket 27 with its cover plate 34 and transparent plate 33 contribute with the chute members 2 and 3 to form an inclosing casing for the rotatable coin support, and the front portion of the casing is provided with the sight opening through which coins or checks in a juxtaposed pocket 22 will be visible.

50 Referring now to the shaft 17 of the rotatable support 16, it will be seen from Figures 5 and 6 that this shaft has fixed to one end of it in any desired manner a cam 38 which, as illustrated, is in the form of a rectangular block. The slots 26 and 30, see Figure 5, have movably mounted in them a member 39 which is in the form of a plate or bar having a recess 40 into which the cam 38 is received when the parts are in assembled position. This recess 40 has its bottom 41 and one side 42 arranged at substantially right angles to each other, so that when the parts are in their normal position, as seen in Figure 5, such side walls will 60 conform to the juxtaposed side walls of the

cam 38, and the coin support 16 will be retained in a stationary position.

The member 39 is retained in the position seen in Figure 5 by means of a spring 43 one end of which bears against the bottom 70 of the member 39 while its opposite end is received in the pocket 44 formed in the chute members 2 and 3 and bears against a set screw 45 in threaded engagement with the coin chute members 2 and 3. The outer 75 end of this screw 45 opens through the members 2 and 3 so that it can be adjusted, when the parts are assembled, to vary the tension of the spring 43. The recess 40, see Figure 3, has its front wall curved as at 46 in order 80 to form a clearance for the cam 38 and the rear wall of the recess is provided with a shoulder 47. Extending through the top wall 48 of the recess 40 is the reduced end of a differential plunger 49, slidable in a 85 differential aperture 50, see Figure 5, and against the enlarged inner end of the plunger 49 bears a spring 51 which is retained in position by means of a cap 52 dove-tailed into the member 39 and secured 90 in position by means of a fastening device 53, such as for example, a screw.

54 designates an operating handle which is pivoted at 55 to the front chute member 2. The handle 54 is provided with a slot 56 95 into which extends a pin 57 projecting from an arm 58 which latter projects rearwardly from the cam controlling member 39.

Referring now more particularly to Figure 4 it will be seen that the rear chute 100 member 3 is provided with a shoulder 59 and the wall of the groove of the rear chute member 3 curves forwardly, as indicated at 60, while the front coin chute member 2 terminates at 61 so that the money or 105 checks passing through the coin chute, after passing from the rotatable coin support 16, will be discharged into the money drawer 62 having closed sides, a closed bottom and an open top. This money drawer is slidable 110 in a money box 63 which is secured to the rear member 3 by means of fastening devices 64. The drawer 62 is provided with a lock 65, the plunger 66 of which bears against the upwardly extending flange 67 115 of the money box 63. The drawer 62 is provided with an operating handle 68.

In many cases arising in practice, it is advantageous to have the second sight opening visible from a plurality of sides of the 120 mechanism and by way of illustration, I have shown in Figure 8 a second sight opening as having the rear cover plate 24 provided with a transparent portion 69 and the plates or blades 20 and 21 are made of 125 transparent material, as illustrated in Figure 8, so that the coins which have been retained in a pocket of the movable support 16 will be visible to the attendant as well as to the purchaser and the manager of the 130

restaurant. It is therefore to be understood that it is within the spirit and scope of my invention to have the second sight opening as well as the first sight opening constructed in such a manner that the coin arrested in proximity to such opening will be visible from a plurality of points or sides of the mechanism.

10 The operation of my novel construction of coin indicating and checking mechanism will now be apparent to those skilled in this art and is as follows:—

15 In practice, I preferably employ one of my devices for each attendant behind the delivery counter of a cafeteria, for example, the attendant or attendants at the fruit delivery counter, the steam table and the dessert table have one of the coin indicating and checking mechanisms supported at the 20 delivery end of their respective counter in a position accessible to the purchaser.

Assuming that the amount of purchase is thirty-seven cents, for example, the purchaser would place thirty-seven cents in the 25 coin chute 5, for example, a twenty-five cent piece, a ten cent piece and two one cent pieces. These would be arrested in their movement through the coin chute 5 by one of the blades 20 or 21 so that they would 30 be visible through the sight opening 6, so that the amount which has been deposited will be visible to the attendant behind the delivery counter, to the purchaser in front of the counter, and also to the manager of 35 the cafeteria. The attendant now moves the handle 54 downwardly thereby causing the member 39 to slide downwardly and the bottom face of the cam 38 will be above the shoulder 47. As the member 39 moves 40 downwardly the plunger 49 will be moved upwardly, thereby placing a tension on the spring 51, so that as soon as the shoulder 47 passes beneath the cam 38 the force of the spring 51 will impart a partial rotation 45 to the cam 38 and the upward or return movement of the member 39 will cause the same to rotate one-quarter of a revolution. The blade, such as 20, on which the coins have been resting, will move forwardly so 50 that the coins will be received in the pocket 22 in rear of such blade, so that these coins will still be exposed to view through the sight opening 37. On the next operation of the handle 54, these coins will pass from the pockets in which they have been retained 55 into the continuation of the coin chute 5, and will be discharged into the money drawer 62, as is apparent.

It will thus be seen that after a purchase 60 is made and the attendant has operated the handle 54, the coins which have been deposited will pass beyond his vision but will still be exposed to the view of the manager of the restaurant, so that the manager has 65 a check on the attendant and the purchaser.

It will now be apparent that I have devised a new and useful coin indicating and checking mechanism which embodies the features of advantage enumerated as desirable in the statement of the invention and 70 the above description, and while I have, in the present instance, shown and described a preferred embodiment thereof which will give in practice satisfactory and reliable results, it is to be understood that such embodiment is 75 susceptible of modification in various particulars without departing from the spirit or scope of the invention or sacrificing any of its advantages.

Having thus described my invention, 80 what I claim as new and desire to secure by Letters Patent, is:

1. In a coin indicating and checking mechanism, a coin chute having a plurality of sight openings visible from the same 85 side of the mechanism, said coin chute being formed by a plurality of members contributing to form a passage and a guide for a coin in such passage, and means to arrest the coins in their passage through the coin 90 chute to successively render them visible through said sight openings.

2. In a coin indicating and checking mechanism, a coin chute having a sight opening visible from the front and the back 95 of the mechanism and a second sight opening visible from the front of the mechanism, said coin chute being formed by a plurality of members contributing to form a passage and a guide for a coin in such 100 passage, and means to successively position the coins to render them first visible at the first sight opening and thereafter visible at the second sight opening.

3. In a coin indicating and checking 105 mechanism, a coin chute having a sight opening visible from the front and the back of the mechanism and a second sight opening visible only from the front of the mechanism, said coin chute being formed by a 110 plurality of members contributing to form a passage and a guide for a coin in such passage, means to successively position the coins to render them first visible at the first sight opening and thereafter visible at the 115 second sight opening, and a coin receiving box into which the coins are discharged from the coin chute.

4. In a coin indicating and checking mechanism, the combination with a coin 120 chute consisting of spaced members each of which serve to guide a coin in its passage through the chute, of means to render a payment deposited in the chute visible to the attendant in rear of the mechanism and 125 to the purchaser in front of the mechanism, and means to thereafter render the payment visible to the purchaser in front of the mechanism without being visible to the attendant in rear of the mechanism.

5. In a coin indicating and checking mechanism, the combination with a coin chute having a sight opening visible from the front and rear of the mechanism, of a movable member having means in the path of a coin to arrest it in a position to render it visible through said sight opening, a cam connected with said member, a cam controlling member, a tension device for the cam controlling member, and means to move said cam controlling member in a direction to increase the tension of said tension device whereby when said means is released the said tension device will actuate the cam controlling member in a direction to effect movement of said movable member.

6. In a coin indicating and checking mechanism, the combination with a coin chute having a sight opening visible from the front and rear of the mechanism and having a second sight opening posterior to said first sight opening, a movable member to arrest the payment passing through the coin chute first in proximity to the first sight opening and second in proximity to the second sight opening and cam actuated means to actuate said movable member.

7. In a coin indicating and checking mechanism, the combination with a coin chute having a sight opening visible from the front and rear of the mechanism and having a second sight opening posterior to said first sight opening and visible only from the front of the machine, a movable member to arrest the payment passing through the coin chute first in proximity to the first sight opening and second in proximity to the second sight opening, and cam actuated means to actuate said movable member.

8. In a coin indicating and checking mechanism, the combination with a coin chute having a sight opening visible from the front and rear of the mechanism and having a second sight opening posterior to the first sight opening and visible only from the front of the mechanism, a rotatable bladed coin support having a series of pockets, said support when in normal position having a blade in position to arrest a coin to render it visible through the first sight opening, and means to move said support to permit the coin to pass beyond the range of the first sight opening and into one of said pockets and to bring such pocket

into a position to render the coin therein visible through the second sight opening.

9. In a coin indicating and checking mechanism, the combination with a coin chute having a plurality of sight openings, of a coin support to successively retain a coin in position to be visible through each sight opening, a cam on said member, a cam slide, a tension device to retain said cam slide in position to prevent movement of said cam and thereby of said member, a handle to move said cam slide in one direction, and means carried by said cam slide to engage said cam and partially rotate it into a position to be engaged by said cam slide on the latter's rearward movement and thereby effect the proper movement of said movable member.

10. In a coin indicating and checking mechanism, the combination with a coin chute having a sight opening, of a movable member to arrest a coin in a position to be visible through said sight opening, a cam on said member, a cam slide having a recess to receive said cam and having certain of its walls conforming to said cam to retain it in a stationary position and provided with a shoulder, a spring pressed plunger carried by said cam slide to engage said cam and turn it into a position to be engaged by said shoulder, a manually actuated handle to move said cam slide in one direction, and a tension device to effect the movement of said cam slide in a reverse direction.

11. In a coin indicating and checking mechanism, the combination with a coin chute having a transparent portion to render the coins visible through a plurality of sides of the mechanism, a money box into which the coins are discharged from said chute, means to arrest the coins in their passage through the chute in proximity to said transparent portion, a tension device for said means, and a manually actuated handle movable in one direction to increase the tension of said tension device, said tension device when said handle is released being operative to move the coin arresting means into position to permit the arrested coins to pass on through the coin chute.
